VOLTAGE REGULATOR TUBE STARTER

Richard W. Lee and Raymond L. Garman, Pleasantville, N. Y., assignors to General Precision Laboratory Incorporated, a corporation of New York

Application December 9, 1948, Serial No. 64,356

8 Claims. (Cl. 315—323)

1

This invention relates to a starter for electronic voltage regulator tubes employed in regulating direct voltage power supply circuits.

The purpose of this invention is to facilitate the starting of electronic voltage regulator tubes under low voltage conditions.

In some types of equipment employing electronic voltage regulator tubes to maintain constancy of supply voltage the available voltage input is limited, so that to maintain a reasonably high regulated voltage it is desirable to have as small a difference as possible between the input to the regulator and the output from the regulator. For example, in the operation of an electronic power supply from lighting circuits of either alternating or direct current, of the usual 115-volt potential, it is desirable to obtain an output voltage as near as possible to the nominal 115 volts, so that high power output can be secured from utilizing equipment containing electronic tubes, the output capacity of which increases rapidly with increase of plate voltage. However, electronic voltage regulator tubes require a voltage to fire them materially higher than their operating voltage, so that when fired from a rectifying power supply operated from alternating/direct current (A.C./D.C.) mains of the usual house lighting circuits of nominally 110 to 125 volts, the maximum feasible regulated voltage has been materially lower. Since in a design for general use extreme variations of lighting circuits between 100 to 140 volts must be anticipated, voltage regulator circuits have heretofore had to be designed to fire on lighting voltages as low as 100 volts. This entails a direct current rectifier output of not over 90 volts and a regulated output materially lower in the usual rectifier designs which operate from a direct current main and as regards rectifiers operating from alternating current mains through step-up power transformers the excess of starting voltage over operating voltage represents a similar loss in efficiency.

This invention permits the use of voltage regulator tubes in such cases producing regulated voltages nearly as high as the rectifier output voltages, and fires the tubes by superimposing on the tube input voltage another voltage so that the sum of the two voltages starts the tube. The last-mentioned voltage thereupon falls to a low value and does not interfere with the normal functioning of the operating voltage regulator tube or of the using equipment.

This invention is particularly applicable to talking motion picture projectors which employ

supersonic frequency current to light the exciter lamp filament, because the supersonic frequency supply voltage can readily be used for helping to start the voltage regulator tube in addition to its regular function.

This invention will be more readily understood from the following detailed description, considered together with the attached drawing in which:

Figure 1 illustrates schematically the circuit embodying the invention and employing resistance-capacitance coupling.

Figure 2 illustrates a circuit employing inductive coupling.

In Fig. 1 a talking motion picture film, exciter lamp, photoelectric cell, amplifier and speaker are arranged to represent a conventional moving picture sound reproduction system.

An exciter lamp 12 emits light which in passing through the sound track of a film strip 11 is modulated by the varying photographic record thereof before being impressed on the cathode 13 of a photocell 14. The anode 16 is energized by a source of rectified and filtered potential diagrammatically illustrated by the terminals 33, 35 through a high resistance 21. The potential is regulated by a voltage regulator tube 23 in series with a ballast resistor 22 across the power supply. The potential variations produced across the resistor 21 as a result of the light fluctuations impinging on the cathode 13 are impressed on the input of a conventional audio amplifier 18 through a blocking condenser 17 connected to the anode side of resistor 21. A loudspeaker 19 is connected to the output of the amplifier 18 and serves to convert the amplified electrical signals to audible sound variations.

In the embodiment disclosed the exciter lamp 12 is indicated as being energized by a source of alternating current whose frequency is above the range of audibility of the human ear. Such an arrangement assures that the light fluctuations which may result from such alternating current energization of the exciter lamp will be at a frequency which is not perceptible and hence do not affect the sound reproduction as far as the ear is concerned.

To obtain such high frequency energization there is provided an oscillator 26 consisting of a thermionic tube 37 and its associated tank circuit which may operate at a frequency of say 30 kilocycles. The output of this oscillator is inductively coupled to the filament of the exciter lamp 12 by means of the transformer 39 and cable 34.

In order that it may be assured that the voltage regulator tube 23 will fire under low voltage conditions and thus exercise its regulating function over the power supply, a fraction of the output voltage of the oscillator 29 is superimposed on the rectified and filtered voltage available at the power supply terminals 33, 35.

To this end a circuit comprising a resistor 28, condenser 27 and a parallel resonant circuit 41 consisting of the inductor 31 and condenser 32 is connected between the plate 36 of the tube 37 and the positive terminal 33 of the potential supply source. The resonant circuit 41 is tuned to the frequency of the oscillator 29 and since this circuit in series with the condenser 27 and resistance 28 is effectively in shunt to the plate coil 38 of the oscillator, substantially the full potential developed across the coil 38 is impressed on this circuit. The resonating efficiency (Q) of the resonant circuit 41 is made of a sufficient value so that while it is not so high as to require critical values of inductance and capacity to maintain resonance with the oscillator nevertheless the current flow through resistance 28 is low and substantially the full voltage generated in the plate coil 38 is developed across the resonant circuit 41. For example, the R. M. S. voltage drop across this circuit for a particular voltage regulator tube should be in the neighborhood of 30 volts. This voltage drop is in series with the supply potential as far as the regulator tube 23 is concerned so that the potential impressed thereon is the sum of the potential available between terminals 33 and 35 and the potential drop across the resonant circuit 41. When, therefore, as frequently happens the line voltage drops to such a low value as to be insufficient to result in the firing of the regulator tube 23, nevertheless the added potential introduced by the resonant circuit 41 is sufficient to raise the total voltage impressed thereon above the firing point so that the regulator tube fires and performs its operating function.

If, for instance, the voltage regulator tube normally operates at 85 volts but requires 115 volts to start as is customary, it may well be that when the power is turned on the voltage at the lighting mains will have decreased to some low value as 100 volts which through losses in the rectifier and filter circuits would produce a voltage of approximately 90 volts across the terminals 33, 35. Under such circumstances, without the use of this artifice, the tube 23 of course could not fire and its regulating function would be lost so that variations in line voltage would produce induced fluctuations in photocell potential resulting in improper sound reproduction. In the instant invention, however, the alternating R. M. S. potential drop of 30 volts existing across the resonant circuit 41 is added to the 90 volts available at the terminals 33 and 35 producing an effective peak voltage at the regulator tube 23 of 132 volts causing it to fire and to regulate the voltage available at the photocell anode 16 in a range of 81 to 86 volts even though the voltage at terminals 33 and 35 varies in a range of 90 to 140 volts. As soon as the tube 23 fires there is placed in effective shunt to the resonant circuit 41 a low impedance to alternating current voltage and the divisional relation between the alternating voltage drop across the resonant circuit 41 and the circuit consisting of the series connected resistor 28 and condenser 27 is changed so that the drop across the resonant circuit is reduced to approximately 10 volts. This reduction in voltage together with

5 the filter circuit consisting of condenser 42 and resistor 21 connected between the anode 16 and cathode 13 of the photocell 14 prevents the imposition of the alternating current on the photocell and hence this high frequency signal does not destroy the regulating properties of the regulator tube.

10 Resistor 28 has a relatively high value commensurate with the voltage drop desired across the resonant circuit 41 when the tube 23 is unfired so that after the tube 23 has fired the oscillator is effectively decoupled from the voltage regulator circuit and the additional loading thereon is reduced to a point where it does not effect normal operation.

15 Several other methods of coupling the oscillator to the voltage regulator circuit could obviously be devised to accomplish the same result of firing the voltage regulator tube while not impairing the regular function of the oscillator, the photoelectric cell or of any other part of the projector equipment. For instance, in Fig. 1 condenser 27 might be omitted if resistor 28 is suitably large, or resistor 28 might be omitted if condenser 27 is suitably small.

20 Another method of coupling employing electromagnetic induction is shown in Fig. 2. Here a circuit similar to that of Fig. 1 in all respects is shown except that the resonant circuit 41 of Fig. 1 has in Fig. 2 been moved to a position of inductive relation with the plate coil 38. The resonant circuit in the new position is shown in Fig. 2 as circuit 43, the inductive relation existing between it and the three coils associated with oscillator tube 37 being indicated by an arrow cutting all four coils. Circuit 43 being tuned to resonance with the frequency of the oscillations generated by the circuits of tube 37, and having a resonating efficiency of Q as described in connection with Fig. 1, will oscillate and produce at its terminals an alternating potential of approximately 30 volts, which will be effectively in series with the direct current potential available at terminals 33 and 35 to start the voltage regulator tube 23. 25 Starting of this tube would then proceed as described in connection with Fig. 1. Decoupling after tube 23 has fired would, however, occur somewhat differently than in the resistor-capacitor coupling case, but no less effectively. Coupling between coil 44 of circuit 43 and the plate coil 38 is made low, yet sufficient under the condition of no loading or light loading to produce ample voltage at the terminals of coil 44. When coil 44 is loaded by the parallel resistance of tube 23 it will, in this loose-coupled condition, be effectively decoupled from the driving coil and its terminal voltage will fall to a low value.

30 What is claimed is:

1. In a device of the character described, a source of direct current potential subject to variation, a regulator tube connected to said source for producing a constant potential output regardless of potential variation of said source, a direct current utilization circuit energized by a circuit including said regulator tube, an oscillator, a resonant circuit connected in series with said regulator tube and said source of direct current potential, a circuit coupling said oscillator output to said resonant circuit including means for decoupling said oscillator and said resonant circuit when said regulator tube is rendered operative, thereby inhibiting the imposition of said oscillator output on said direct current utilization circuit.
2. A device in accordance with claim 1 in which

said coupling circuit comprises an electrostatic capacitance.

3. A device in accordance with claim 1 in which said coupling circuit comprises an electrical resistance.

4. A device in accordance with claim 1 in which said coupling circuit comprises two inductors having mutual inductance.

5. A voltage regulator tube starting circuit comprising a voltage regulator discharge tube, a 10 source of direct voltage higher than the operating tube voltage but lower than the firing voltage of the tube, an electrical connection from one terminal of said source to one terminal of said tube, a protective resistor, an electrical connection from a first terminal of said protective resistor to the remaining terminal of said tube, an electronic generator of alternating current of a frequency above audibility, a parallel-tuned inductance-capacitance circuit tuned to the frequency of said generator, an electrical connection from the remaining terminal of said direct voltage source to a terminal of said inductance-capacitance circuit, an electrical connection from the remaining terminal of said inductance-capacitance circuit to the second terminal of said protective resistor, a coupling resistor, a coupling condenser, an electrical connection from one terminal of said coupling resistor to one terminal of said coupling condenser, an electrical connection from the remaining terminal of said coupling resistor to a high output voltage point within said electronic generator, and an electrical connection from the remaining terminal of said coupling condenser to said second terminal of the protective resistor, whereby the peak voltage of said electronic generator output is superimposed on said direct voltage and whereby the two voltages together exceed the firing potential of said voltage regulator tube.

6. In a device of the character described, a source of direct current potential subject to variation, a regulator tube connected to said source for producing a constant potential output regardless of potential variation of said source, a direct current utilization circuit energized by a circuit including said regulator tube, an oscillator, a resonant circuit connected in series with said regulator tube and said source of direct current

potential, a resistance condenser circuit connected between said oscillator output and the terminal of said resonant circuit remote from that connected to said direct current source whereby the proportionate amount of alternate current potential drop produced across said resonant circuit is greatly reduced on operation of said regulator tube.

- 5 7. In a device of the character described, a source of direct current potential subject to variation, a regulator tube connected to said source for producing a constant potential output regardless of potential variation of said source, a direct current utilization circuit energized by a circuit 15 including said regulator tube, an oscillator, a resonant circuit connected in series with said regulator tube and said source of direct current potential, said resonant circuit including an inductance coil loosely coupled to the output of said oscillator 20 whereby the resistance loading imposed thereon by the operation of said regulator tube effectively decouples said inductance coil and inhibits the imposition of said oscillator output on said direct current utilization circuit.
- 25 8. A starter for a voltage regulator tube connected to a source of direct current potential subject to variation, comprising an oscillator having an output coil connected in its plate circuit, a resonant circuit tuned to the frequency of the 30 signal impressed on said output coil, a circuit connecting said resonant circuit in series with said voltage regulator tube and said source of direct current potential and a coupling circuit comprising a condenser and a resistor connected 35 in series between one terminal of said resonant circuit and the plate terminal of said output coil.
